UNITED STATES PATENT OFFICE.

LOUIS LANDMANN, OF JEFFERSON CITY, MISSOURI.

SANITARY VENTILATING WATER-CLOSET BOWL.

1,261,561.

Specification of Letters Patent.

Patented Apr. 2, 1918.

Application filed November 9, 1917. Serial No. 201,096.

To all whom it may concern:

Be it known that I, LOUIS LANDMANN, a citizen of the United States, residing at Jefferson City, in the county of Cole and State of Missouri, have invented Sanitary Ventilating Water-Closet Bowls, of which the following is a specification.

This invention has relation to water closet bowls, and has for an object to provide means therein to permit the withdrawal therefrom of foul odors and to thoroughly ventilate the same.

Another object of the invention is to provide a water closet bowl for the purpose specified, embodying an annular air chamber encircling the mouth of the bowl and in communication with the interior thereof, said chamber being adapted to be connected to a flue in which a natural or artificial draft exists, whereby to remove foul odors from the bowl and to thoroughly ventilate the same.

Another object of the invention is to provide a water closet bowl having the characteristics above named, and which will be also effective to ventilate the toilet room by withdrawing the air therefrom, through the water closet bowl in the manner above set forth.

30 A still further object of the invention is to provide a water closet bowl having the characteristics above described and which is simple in construction, thoroughly efficient in operation, calculated to interfere in no manner with the discharge of water, into or out of the bowl, and which may be installed at a low cost.

In addition to the foregoing, this invention comprehends improvements in the details of construction and arrangements of parts, to be hereinafter described and particularly pointed out in the appended claims.

In the accompanying drawings, in which similar and corresponding parts are designated by the same characters of reference throughout the several views in which they appear:

Figure 1 is a view in vertical section of a water closet bowl, constructed in accordance with my invention, and

Fig. 2 is a view thereof in plan.

With reference to the drawings, 10 indicates generally a water closet bowl of conventional form, having a discharge conduit 11 leading from the rear portion thereof as indicated. The front wall 12 is curved

down to the base 13 as at 14. The edge of the mouth of the bowl is enlarged to form an inner roll 15 which is formed with a plurality of apertures 16 directed into the bowl 60 and communicating with the interior of the roll, the same being hollow. A water supply pipe 17 is connected to the channel within the roll to supply water thereto which issues through the perforations and serves to 65 flush the bowl.

The inner roll is housed within a casing 18, which, in cross section, surrounds the inner roll for more than one-half its circumference, the perforations 16 being exposed. 70 The casing surrounds the top edge of the bowl and thereby forms in effect an outer roll. As will be noted the outer casing is disposed in spaced relation to the inner roll and is held in such relation by means of 75 integrally formed studs 19 which are arranged around the bowl in uniform spaced relation as shown.

A wall 20 is provided in spaced relation to the walls of the bowl and base thereof, said 80 wall, at the front of the bowl extending from the upper edge thereof to the base. At the rear of the bowl, however, the wall 20 extends from the upper edge of the bowl downward only a short distance. In this 85 manner an annular channel 21 extends around the bowl, communicating at all points with the space between the inner and outer rolls, and tapering downward, from the rear of the bowl to the base where the 90 space 21 communicates with a circular opening 22 therein.

When the bowl is installed, the opening 22 in the base is connected to a pipe 23 which communicates with the flue 24 which extends 95 through the building and opens above the roof, thus providing a vertical column in which a natural draft is created and continues at all times. If desired, however, an artificial or forced draft may be induced in 100 the flue.

In any event, foul odors from within the bowl are constantly drawn out through the flue, being taken from the bowl through the channel surrounding the inner roll and 105 through the space between the front wall of the bowl and the wall 20.

It will be obvious, that if the bowl is installed in a toilet or bath room the air therewithin will be drawn into the bowl and expelled through the flue, thus permitting the air of the room to be constantly replaced

with fresh air, without the use of any ventilating system.

While I have illustrated and described my invention with some degree of particularity, I realize that in practice various alterations therein may be made. I therefore reserve the right and privilege of changing the form of the details of construction, or otherwise altering the arrangement of the correlated parts, without departing from the spirit of the invention or the scope of the appended claims.

Having thus described my invention, what I claim as new and desire to secure by Letters Patent is:

1. The combination with a water closet bowl, of a hollow perforated roll at the upper end thereof, a wall arranged in spaced relation to the bowl and exteriorly of the same, an annular inwardly directed transversely curved flange formed at the upper end of the wall and overlying the roll to protect the same.

2. The combination with a water closet bowl, of a hollow perforated roll at the

upper end thereof, a wall arranged in spaced relation to the bowl and exteriorly of the same, an inwardly directed annular flange formed at the upper end of the wall and overlying the roll to protect the same, and 30 studs interposed between the roll and flange.

3. In a water closet bowl, the combination of a hollow annular roll forming the upper edge of the bowl and partly encircling the roll transversely and in spaced relation to 35 form an air chamber, the roll being perforated to discharge water into the bowl through the chamber, and a wall formed in spaced relation to the wall of the bowl to define a passage which tapers downwardly 40 and forwardly and is in communication at its large end with the chamber and at its small end with an opening to be connected to a flue, whereby, to ventilate the bowl.

In testimony whereof I affix my signature 45 in the presence of two witnesses.

LOUIS LANDMANN.
